UNITED STATES PATENT OFFICE.

WALLER CROW AND JOHN C. SCHAFER, OF PITTSBURGH, PENNSYLVANIA, ASSIGNEES
TO SCHAFER ENGINEERING & EQUIPMENT CO., OF PITTSBURGH, PENNSYLVANIA,
A CORPORATION OF PENNSYLVANIA.

ELECTRIC SEPARATOR.

Application filed August 28, 1920. Serial No. 406,667.

To all whom it may concern:

Be it known that we, WALLER Crow and JOHN C. SCHAFER, each a citizen of the United States of America, residing at Pittsburgh, Allegheny County, Pennsylvania, have invented new and useful Electric Separators, of which the following is a specification.

This invention relates to mechanisms for 10 grading or the separation of divided materials into particles of different sizes.

This invention has utility when incorporated as an electric vibrator and as herein shown is equipped with a perforate material carrying floor or screen.

Referring to the drawings:

Fig. 1 is a side elevation, with parts broken away, of an embodiment of the invention in an inclined screen;

20 Fig. 2 is a wiring diagram of the device;

Fig. 3 is an elevation of one of the tightening devices;

Fig. 4 is a section of the screen tightening device of Fig. 3;

25 Fig. 5 is a perspective view of electro-magnet and armature frame members;

Fig. 6 is a fragmentary plan view of the apparatus of Fig. 1; and

30 Fig. 7 is an end elevation of the apparatus of Fig. 1; with parts broken away.

A base 1 is provided upstanding from which, as two pairs, extend stems 2. The material carrying device proper comprises a pair of angle iron side bars 3 of the main 35 frame connected by bracing members 4 therebetween. The side angle frame members 3 are shown as providing seats for auxiliary angle bars 5 which by means of bolts 6, may have a platform attached thereto.

40 The perforate platform is herein shown as a screen 7. Owing to the quick action with limited amount of travel, it is desired that the platform 7 be drawn very taut and in effecting adjustment thereof, bolts 8 are provided extending through the angle frame 3, which may be tightened up by the nuts thereon. It is desirable further that this angle 5 be not tilted in this drawing up and to avoid such, a bar 9 may be inserted

45 between the upstanding legs of the angles 3 and 5. The bar 9 is selected for size of adjustment and drawing up of the bolt 8 may crowd in final tension setting.

Connected to each side member 3 is an

upper bracket 10 and a lower bracket 11, 55 each carrying a sleeve 12 guided on the stem 2. These stems 2 of the sectional supporting means for the frame are anchored to the main base 1 by nuts 13.

Carried by the base 1 between the stems 60 2 are shown base plates 14 upstanding from which are pedestals 15 carrying laminations 16 of an alternating current electro-magnet. On one leg of each of these laminated electro-magnets or members is a coil 17. To 65 one side of each coil 17, the pedestal 15 carries a bearing pin 18 for a rock arm or lever 19 overhanging the one side of the leg of the electro-magnet 16 about which extends the coil 17. This arm portion 19 70 carries a laminated armature 20 which is the armature proper of this magnetic device. This lever 19 remote from the armature 20 has an eye or sleeve 21 fitting about or coacting with the stem 2.

75 Mounted on each stem 2 above the platform sleeve 12, is a helical spring 23, the tension of which spring may be adjusted by nuts 24 on the stem 2. Of course, as herein shown the loading of the platform 80 is on the sleeve 12 and this provides a normal means for keeping the device loaded down so that the tilt of the armature lever 21 is down against nut 22 which may be adjusted to limit the rocking of the armature 20 away from the plate of the electro-magnet 16. In practice it is very desirable, owing to the alternations of the current supplied to the coil 17, that the spring 23 be of such strength and speed, compared 85 with the load of the main frame, that actual vibration is effected in the operation of the device. The cycle of the current is one factor, the loading of the frame or screen is another factor, and as between these there 90 may be the adjustment of the spring not only as to the nut 24 but as to the distance of throw effected by the armature by adjusting the nut 22.

95 While the coils of the magnet may be in step as herein shown in parallel, it is also practical to have them out of step to thereby magnify the vibrations of the screen by bucking each other. With the coils connected in step as herein shown, a main line 25 100 may pass by switch 26 to a single phase alternator 27 and from such source of the current supply by line 28 to the coils 17.

This screen is a simple form of mechanical and electromagnet support and is effective for fine separations for clay products, pottery works materials, or even bolting or other industrial separations, handling the materials in a very effective and uniform manner.

What is claimed and it is desired to secure by Letters Patent is:

10. 1. A material carrying platform having a screen and a frame for the screen, supporting means for the frame embodying relatively movable members, and alternating current electromagnet lifting means coacting with the supporting means movable members for shifting the frame.
15. 2. A material carrying platform, carrying means for the platform including magnets and armatures pivotally connected to the magnets to provide platform shaking joints in the carrying means.
20. 3. A material carrying platform, carrying means for the platform including a pair of alternating current electro-magnets, and an armature pivotally connected to each magnet and loaded by the platform on the opposite side of the pivotal mounting from the electro-magnet.
25. 4. A material carrying platform, a base, guide stems carried by the base, sleeves carried by the platform coacting with the stems, a rockable armature coacting with each stem, and electro-magnetic means for vibrating the armatures.
30. 5. A material carrying platform, a base,

guide stems carried by the base, a rockable armature coacting with each stem, adjustable means limiting the depression of the armatures, and electro-magnetic means for vibrating the armatures.

6. A material carrying platform, a base, guide stems carried by the base, sleeves carried by the platform coacting with the stems, a rockable armature coacting with each stem, electro-magnetic means for vibrating the armature, and yieldable means coacting to maintain the platform sleeves against the armatures.

7. An inclined frame, a perforate platform in the frame, means for drawing said platform taut, four guide stems for the platform frame, an alternating current electromagnet adjacent each stem, a helical spring on each stem, a sleeve carried by the frame for each stem coacting with the stem below the helical spring, and armatures actuatable by the magnets coacting with the sleeves for shaking the frame.

8. An electro-magnet vibrated screen, mounting means giving the screen a position of rest, springs for resisting the electro-magnet throw of the screen and means for adjusting toward the position of rest the resistance of the springs to the electro-magnet independently of changing the position of rest for the screen.

In witness whereof we affix our signatures.

WALLER CROW.
JOHN C. SCHAFFER.
